UNITED STATES PATENT OFFICE.

JAMES BOWDITCH, OF ISLINGTON, NEW SOUTH WALES, AUSTRALIA.

BOAT-DROPPING GEAR.

1,257,577.

Specification of Letters Patent. Patented Feb. 26, 1918.

Application filed September 14, 1917. Serial No. 191,463.

To all whom it may concern:

Be it known that I, JAMES BOWDITCH, a subject of the King of Great Britain and Ireland, residing at 74 Maitland road, Islington, 5 ton, in the State of New South Wales, Commonwealth of Australia, have invented certain new and useful Improvements in Boat-Dropping Gears, of which the following is a specification.

- 10 This invention relates to appliances installed in ships' boats for the attachment thereto of lifting and lowering tackle and the release of such tackle as and when required.
- 15 And the object of the invention is to provide gear whereby the tackle may as occasion requires be instantly released from each end of the boat simultaneously by one operation and the attachment of the gear may 20 be effected at each end independently, so that the tackle having been attached at one end remains so attached while the tackle is attached to the other end. In other words the gear is so constructed and arranged that 25 while release of the tackle is effected by one operation, its attachment requires two operations of which one remains effective while the other is performed.

The invention consists of gear installed 30 in each end of the boat as hereinafter described with reference to the accompanying drawings and more particularly specified in the appended claims.

In the drawings:—

- 35 Figure 1 is a broken perspective view of a boat fitted with gear according to this invention, the boat shown being double ended, but for distinction the left hand end in the drawing is hereinafter referred to as the stern while the right hand end is referred to as the bow.
- 40 Fig. 2 is a sectional perspective of the portion of the gear fitted in the stern, and

45 Fig. 3 a similar view of the portion of the gear fitted in the bow.

Fig. 4 is a longitudinal sectional elevation of part of the stern end of the boat with the gear therein (in partly sectional elevation) engaging the tackle, and showing 50 in dotted lines the release position of the parts, and

Fig. 5 is a similar view of part of the bow end of the boat and its gear.

55 Fig. 6 is a side elevation of the stern gear which may be operated without affecting the bow gear, showing it opened by in-

dependent means ready to receive the tackle link for attachment purposes.

Fig. 7 is a sectional plan on line 7.7 of Fig. 4, and

Fig. 8 a sectional plan on line 8.8 of Fig. 5, while

Fig. 9 is sectional elevation on line 9.9 of Fig. 7.

It is to be understood that I do not confine the application of my invention to a boat of the particular type illustrated, nor is my invention confined to the method illustrated and hereinafter described of mounting the gear in the boat as it is obvious that with different types of boats this may be modified in various ways within the scope of the invention. It is also to be understood that the parts referred to as being fitted in the bow of the boat may be fitted in the stern and the parts in the latter fitted in the bow.

The boat 10 as illustrated is partially decked at the stern and bow as at 11 and 12 respectively, and slots 13 and 14 are provided in said decking to permit the passage of tackle links 15 and 16 attached to the boat tackles 17 and 18 (see Figs. 4 and 5.)

In the stern of the boat the gear which is indicated generally in Fig. 1 by the numeral 19 and is illustrated in clearer detail in Figs. 2, 4, 6, 7 and 9, comprises a post 20 stepped in the keel 21 and secured by a nut 22, said post passing through the bilge-board 23 and having an offset lug 24, a slotted head 25, and terminating in an oppositely offset bracket or lug 26 secured against the under side of the decking 12 by means of a bolt 27. To the lug 24 is pivoted on pin 28 the bell crank 29, the shorter and downwardly directed arm of which is pivotally connected to a rod 30 running longitudinally of the boat above the bilge board under a cover plate 31 attached to the latter and connected to the gear (hereinafter described) at the bow of the boat. The other arm of said bell crank 29 constitutes an operating lever 32 terminating in a foot pedal 33. Associated with said lever 32 is an auxiliary lever 34 also pivoted on pin 28, but on the opposite side of lug 24 to the bell crank 29, its longer arm being terminally rabbeted as at 35 to partly underlie the pedal 33 of lever 32 (see Figs. 6, 7 and 9) while its shorter arm is pivotally connected to the lower end of a push rod 36 having a bifurcated head 37 in which is pivoted one end of a pawl 38 the

- other end of which is pivoted at 39 in the slotted head 25 of the post 20 so that said pawl also constitutes a link connecting the respective heads of the post and push rod.
- 5 A hook 40 to engage the tackle link 15 passed downwardly through slot 13 in decking 11 as in Fig. 4, is pivotally mounted in the slotted head 25 of post 20 on pin 41 positioned vertically below said slot 13, said hook having a tail 42 extending into the bifurcated head of push-rod 36 and provided with a notch 43 which is engaged by the corner 44 of pawl 38 to retain the hook point 45 in contact with the lug 26 and prevent escape of the tackle link 15, as shown in full lines in Fig. 4. The levers 32 and 34 are prevented from accidental operation by means of a guard chain 46 secured at one end of the post 20 and fitted at the other end with a shackle 47 the pin of which is (when the hook 40 is closed and the levers register together as in Fig. 4) passed through the holes 48 and 49 in said levers respectively so that neither of them can be depressed until the pin is withdrawn.
- 10 Gear is provided in the bow of the boat and this is indicated generally in Fig. 1 by the numeral 50 and detailed more clearly in Figs. 3, 5 and 8.
- 15 The bow gear comprises a post 51 with lug 52, slotted head 53, and top lug or bracket 54 which is attached to the decking 12 by bolt 55; also a push-rod 56 with bifurcated head 57, a pawl 58 pivoted thereto and to the head of the post 51, and a hook 59 with tail 60 extending into the bifurcated head 57 of the push rod 56. The whole of these parts are constructed and relatively arranged in the same form and manner as 20 the corresponding parts of the stern gear hereinbefore described.
- 25 To the lug 52 is pivoted on pin 61 a bell-crank 62 to the shorter and downwardly directed arm of which is pivotally attached the connecting rod 30 extending from the stern gear under the guard plate 31, the two sets of gear being thus connected. The longer arm of said bell crank 62 is pivotally connected to the lower end of the push-rod 56.
- 30 It will be seen that when the gears are closed as in Figs. 2 and 3, 4 and 5, the pawls 38 and 58 prevent the opening of the hooks 40 and 59 so that the tackle links 15 and 16 are held by their respective hooks for the 35 lifting or lowering of the boat. When however it is desired to drop the boat the levers 32 and 34 are first released by withdrawing the pin of shackle 47 on guard chain 46 and downward pressure is then applied to pedal 33 of lever 32 the depression of which also depresses lever 34 which partly underlies said pedal 33. The depression of lever 32 partially rotates crank 29 which being connected by rod 30 to bell-crank 62 of the bow 40 gear effects partial rotation of the latter and

raises the push rod 56. At the same time lever 34 by its depression raises push-rod 36. The result of the upward movement of push-rod 36 is to lift the pawl 38 from the notch 43 in the tail 42 of hook 40, and shoulder 64 contacts with said tail and by raising it 45 opens the hook. Simultaneously push-rod 56 operates to open hook 59 in exactly the same manner so that tackle links 15 and 16 are freed at the same time.

75 To open the stern hook only, as may be required for attaching tackle to one end of the boat at one time, lever 34 is depressed (lever 32 remaining unaffected) which results in push-rod 36 being raised to open 80 hook 40.

Closure of the hook or hooks is effected by the weight of the push-rod or push-rods, the tail or tails of the hook or hooks being depressed by the pawl or pawls which engages 85 or engage in the locking position before mentioned to hold the hook or hooks closed.

What I claim and desire to secure by Letters Patent is:—

1. Boat dropping gear comprising at each 90 end of a boat, a fixed post, a hook pivoted to the head of said post to engage boat tackle, a pawl engaging said hook to maintain its point against a fixed abutment and means for releasing said pawl and allowing said 95 hook to open; in combination with a lever, a rod connecting the pawl releasing means at each end and actuated by said lever, and means for releasing the pawl and thereby opening the hook at one end independently 100 of the other.

2. Boat dropping gear comprising at each end of a boat, a fixed post, a hook pivoted to the head of said post to engage boat tackle, a tail on said hook, a pawl engaging said tail 105 to maintain the hook point against a fixed abutment and pivoted at one end to said post, and a push-rod pivoted at its upper end to said pawl and engaging the tail of said hook; in combination with, at one end, a 110 lever pivoted to said post and pivotally connected at one end to said push-rod, a bell-crank pivoted to said post, one arm of said bell-crank constituting a lever partly overlying the first mentioned lever, the other arm 115 of said bell-crank being attached to a connecting rod extending to the gear at the other end; also in combination with, at the other end, a bell-crank pivoted to the post, one arm of said bell crank being pivotally 120 attached to and movable by said connecting rod, and its other arm pivotally attached to the push-rod.

3. Boat dropping gear comprising at one end of a boat, a fixed post having a slotted head terminating in a lug or bracket, a hook to engage boat tackle pivoted in said slotted head and having a tail provided with a notch, a pawl pivoted at one end to said post and engaging the notch in said tail to main- 125 130

tain the hook point against said lug, a push-rod having a bifurcated head which embraces the extremity of said tail and in which the other end of said pawl is pivoted, 5 a lever to operate the gear at one end only pivoted to said post and having one end pivotally attached to said push-rod, a bell-crank also pivoted to said post one arm of 10 said bell-crank constituting an operating lever and terminating in a pedal overlying part of the first mentioned lever; in combination with at the other end of the boat, a fixed post with slotted head, a hook pivoted

and having a notched tail, a pawl engaging said notched tail, and a push-rod pivotally connected to said pawl and embracing said tail, all as before specified, a bell-crank pivoted to the post and to one arm of which 15 said push-rod is pivotally attached; in further combination with a rod connecting the bell-cranks at each end to effect simultaneous operation of the tackle engaging hooks at each end on depression of the said pedal.

Signed at Sydney, New South Wales, Australia, this 16th of August, A. D. 1917.

JAMES BOWDITCH.
